FOLDING KNIFE

Barry Bertram Wood, 38 S. Venice Blvd.,
Venice, Calif. 92091

Filed Apr. 1, 1971, Ser. No. 130,549

Term of patent 14 years

Int. Cl. D8—03

U.S. Cl. D8—99

FIG. 1

FIG. 2

FIG. 3

FIG. 4

FIG. 5

FIG. 6

FIG. 1 is a perspective view of a folding knife showing my new design;

FIG. 2 is a side elevational view thereof, showing the side not shown in FIG. 1;

FIG. 3 is a top plan view thereof;

FIG. 4 is a bottom plan view thereof;

FIG. 5 is a front elevational view thereof; and,

FIG. 6 is a rear elevational view thereof.

I claim:

The ornamental design for a folding knife, substantially as shown.
